UNITED STATES PATENT OFFICE.

AUGUST W. CORDES, OF NEW YORK, N. Y.

WALL CONSTRUCTION.

1,231,711.

Specification of Letters Patent.

Patented July 3, 1917.

Application filed October 21, 1915. Serial No. 57,052.

To all whom it may concern:

Be it known that I, AUGUST W. CORDES, a citizen of the United States, and a resident of the borough of Manhattan, city, county, and State of New York, have invented certain new and useful Improvements in Wall Construction, of which the following is a specification.

My invention relates to a form of wall construction particularly adapted for parapet walls and designed to bring about more perfect results than have heretofore been accomplished in connection with the employment of counter flashings. The invention is more particularly adapted for use in connection with walls composed of bricks or the like cemented together so as to form a straight line of cement, or walls formed of concrete or coalescent material.

I have found that one of the main defects of the customary methods of endeavoring to protect the edge of the roofing material results from a combination of activities on the part of forces of nature and that to properly meet and counteract such forces a reconstruction or a rearrangement is required with respect to those means which coöperate with the edge of the roofing material to protect it. It has been customary to make cap or counter flashings of metal strips bent at right angles, one part of the strip being built in a horizontal direction into the mortar joint of the brick work while the other part of the strip hangs down to form a cap to cover the edge of the roofing material which has been turned up from the roof against the walls and under said counter flashing. In concrete walls a cut or recess is built or formed, and into this recess the edge of the roofing is turned and made tight by calking. In these constructions I find that at the point where the cap flashing enters the wall, water is apt to seep back into the wall and by the action of frost and expansion and contraction, to loosen the cap and require repairs, or that snow and draft is blown under the open joint between the roof and the flashing, thereby enabling moisture to enter the building. So far as concrete walls are concerned, the action of the elements is manifestly continuously antagonistic to a calked structure. In order to furnish the edge of the roofing material with proper protection against the manifold dis-

advantages of existing structures, I so fashion the counter flashing or so incorporate it in the coalescent material that its upper face is elevated within the coalescent material above the point where the cap projects from the wall face. In other words at some point in the interior of the wall the top line of the flashing is higher than it is at the face of the wall. Any water, whether in the form of liquid or snow, whether tending to seep or to be blown against the wall, will thus be met with a substantial resistance tending to eject the water from the wall, so that even should some penetration occur it cannot overcome to any material extent the automatic action of the metal due to its special shape in the wall in supplying an easier means of egress of the water out of the wall than any means by which the water can enter the wall. Expansion, the heat of the sun and other forces playing upon my type of wall construction no longer assist as means to inflict injury, but are converted into positive forces to aid in keeping the moisture out. Other details of the invention connected with the development of the idea above described are to be found in the combination with the means for forming a specially strong key with the mortar and, where concrete walls are dealt with, in so arranging the metal of the flashing that a closed pocket will be formed in the concrete. In both cases, that is walls of brick or concrete, that part of the metal extending from the wall is bent back inwardly upon itself so as to adapt it to form a locked joint with the edge of the roofing material when bent back in outward direction. Other details relating to the development of the invention will appear from the specification.

The invention is illustrated in the drawings in which Figure 1 is a vertical section through a wall composed of brick, showing the initial position of the cap flashing.

Fig. 2 is a similar section showing the final finished position of flashing and roofing material.

Figs. 3, 4 and 5 illustrate in perspective details relating to special forms of metal flashing.

Fig. 6 is a vertical section through a section wall showing the manner in which the metal flashing is incorporated therein.

Fig. 7 is a similar view through an adj-

cent portion of the wall and flashing of Fig. 6, with the flashing and roofing material in final finished shape.

Fig. 8 is a sectional view taken on line 5 8—8 of Fig. 6.

Fig. 9 is a detail of the metal flashing, the forward part being broken off.

Figs. 10 and 11 are vertical sectional views showing a modified form of structure.

10 In the drawings 1 represents a cap flashing. This element is generally constructed in strips approximately six feet in length. Where two of such strips 1 adjoin, it is advisable to use a key such as shown at 2 in 15 Fig. 3.

When the courses of brick 3 have reached the proper height, the strips 1 are placed thereon as shown in Fig. 1, in which position they are self supporting. In the particular embodiment shown in Figs. 1 and 20 3, the strip 1 is formed in a slanting direction, being supported in this position by the bent edge 4 which is integrally fashioned with the strip 1. In Fig. 4, the inner part 25 of the strip has a configuration in which a downwardly bent flange 5 alternates with the projection 6, the flanges 5 serving to support the strip while the flanges 5 and 6, like the flange 4 of Fig. 1, tend to anchor 30 the strips firmly in the mortar joint. In Fig. 5, the downwardly projecting flanges 5 serve the same purposes as the flanges 5 of Fig. 4. In this type of construction 35 illustrated in Figs. 3 and 4, the mortar can readily enter beneath the inclined surface of the strip 1. The apertures 7 of Figs. 4 and 5 may be used for the purpose of inserting a nail or pin at appropriate distances apart to aid in supporting the strip 40 in its initial position. After these strips have been properly placed the mortar joint is formed and the upper courses of the brick are continued to complete the wall. The outer end of the strip is fashioned into the 45 form of a hook 8, which projects from the face of the wall. The strips being made of soft metal enables the hooks 8 to be bent into the dotted position of Fig. 1, which enables them to pass over the projecting edge 9 50 which is formed in the roofing material 10. The two parts are then hammered down until they assume the position shown in Fig. 2. Where the two hooks, 9 of the roof flashing, and 8 of the cap flashing, come 55 together, some asphaltic cement, or some plastic asphaltum, or wax or some other suitable substance may be introduced as the hooks are folded together in order to make the joint more perfectly water-tight.

60 When the invention is employed in constructing concrete walls I use the device as illustrated in Figs. 6, 7 and 8. In this case the strips 1 are folded as shown, the metal being bent upon itself at the inner portion as more clearly shown in Fig. 9,

while the hook 8 lies flat against the face of the apron 11 of the strip which in itself terminates in the rearwardly extending projection 12. The strip 1 bent in this fashion is an irregularly shaped tube forming a 70 closed pocket into the interior of which cement cannot enter while the projections 5, 6 and 12 supply anchoring means for supporting the strip permanently in the concrete. In order to incorporate this strip in 75 the concrete wall, I employ a bracket 13 notched at 16 which supports the strip 1 against the wooden form 14. The brackets 13 are disposed at intervals and are nailed to the form by the nails 15. After the cement has set, the forms 14 are removed, leaving the brackets 13 and the nails 15 together with the strip 1 permanently in place in the wall. The points of the nails are clipped off or hammered down. The 80 hook 8 of the strip 1 may then be bent in an outwardly direction as indicated by dotted lines in Fig. 7, leaving a recess or pocket in the face of the wall. The hook 8 is then united with the roof flashing as 85 described in connection with the brick walls and when hammered down, the entire structure takes the position shown in Fig. 7. The bracket 13 may be formed in many different ways to answer the same purpose. By shaping it as shown this permits the concrete to run all around the bracket which anchors it very firmly. Additional anchoring means such as the apertures 17 may also be employed to let the concrete bond through and 90 to prevent the bracket from being in any way displaced when the wooden form is torn from the nails 15. In order not to enlarge the pocket which is permanently formed in the concrete by the strip 1, the 95 hook 8 is in some cases bent rather close together in the initial construction of the strip which makes it necessary subsequently, when the hook is bent so as to project from the wall, to open the hook itself in order to 100 have it accommodate the bent edge of the roof flashing. Figs. 10 and 11 show variations in the construction of the strip 1. In these two figures, the strip 1 is composed 105 of resilient material. By inserting the hook 110 shaped end of the roof flashing 18 into the pocket and beneath the edge of the hook 8, the edge of the hook 8 snaps back and enters into locking engagement with the hook 18. Many variations in form and detail may be employed, it being important, however, to observe the direction in each case that the point where the strip 1 projects from the wall shall be lower than some other part of the strip permanently incorporated and held in place in the cementitious material.

What I claim is:

1. A wall construction comprising as an integral part thereof a cap or counter flash- 130

ing, one part of which is embedded in the wall in an upwardly slanting position, means for maintaining the said elevated part in predetermined slanting position during the building up of the wall, the inner portion of the cap terminating in an apron to form a closed pocket with the forward end of the cap to prevent the entry of liquid cementitious material, the projecting part of the cap being bent back upon itself to form a hook adapted to engage and form a joint with the edge of the roofing material.

2. A wall construction comprising as an integral part thereof a series of strips placed edge to edge, a key between the same, said strips constituting a cap or counter flashing, one part of which is embedded in the wall in an upwardly slanting position, means within said wall for maintaining the said slanting part in predetermined position during the building up of the wall, one edge of said cap being bent back upon itself to form a hook adapted to engage and form a joint with the edge of the roofing material.

3. The combination of a wall, a member 25 embedded in said wall and forming a tubular pocket therein, a resilient flange extending longitudinally along an outer edge of said member to longitudinally close the outer opening thereof, a sheet of material adapted 30 to be inserted into said pocket against the tension of said member and a flange on said sheet of material adapted to hook behind the flange of said pocket forming member, whereby withdrawal of said sheet of material 35 from said pocket is resisted.

4. The combination of a wall, a cap or counter flashing extending into and secured in said wall, a sheet of material, and hooks located respectively on said cap or counter 40 flashing and on said sheet of material at opposed edges thereof, said hooks being interlocked with each other to resist separation of said sheet of material and said cap or counter flashing from each other. 45

In testimony whereof I have hereunto set my hand.

AUGUST W. CORDES.
